UNITED STATES PATENT OFFICE

127,808

DESIGN FOR AN ANIMAL BED

Daniel J. McGillicuddy, Malden, Mass.

Application November 22, 1939, Serial No. 88,405

Term of patent 14 years

To whom it may concern:

Be it known that I, Daniel J. McGillicuddy, a citizen of the United States and a resident of Malden, in the county of Middlesex and Commonwealth of Massachusetts, have invented a new, original, and ornamental Design for an Animal Bed, of which the following is a specification, reference being had to the accompanying drawing, forming a part thereof. Fig. 1 is a view in perspective of an animal bed showing my new design, and Fig. 2 is an end view thereof.

The dominant feature of my design consists

of tubing bent to form two relatively long parallel base sections and two end sections in combination with a mattress disposed within the frame below the level of the tops of the end sections, the mattress being supported at its four corners on the frame, all as shown in the drawing.

I claim:

The ornamental design for an animal bed substantially as shown and described.

DANIEL J. McGILLICUDDY.
